UNITED STATES PATENT OFFICE.

HAROLD L. BLOOD, OF PLAINFIELD, NEW JERSEY, ASSIGNOR TO NILES-BEMENT-POND COMPANY, OF NEW YORK, N. Y., A CORPORATION OF NEW JERSEY.

FEED MECHANISM FOR PLANERS.

Application filed March 24, 1921. Serial No. 455,058.

To all whom it may concern:

Be it known that I, HAROLD L. BLOOD, a citizen of the United States, residing at Plainfield, in the county of Union and State 5 of New Jersey, have invented certain new and useful Improvements in Feed Mechanism for Planers, of which the following is a specification.

This invention relates to planers and particularly to the tool feeding and traversing mechanism of planers of the type described and illustrated in Patents No. 1,299,192 to Keefer & Greenleaf, and 1,321,203 to Greenleaf & Blood. The primary object 10 of the invention is to simplify the feeding mechanism now in use on such machines and to provide a single mechanism through which both the desired feeding and traversing of the tool may be accomplished without the employment of clutches or other shifting devices.

More specifically it is an object of the invention to connect the tool feeding and traversing screws to a feed motor through 15 a mechanism comprising a lost motion box, the operating means within the box comprising relatively adjustable members whereby the amount of lost motion of the tool feed shaft may be varied to vary the 20 amount of feeding movement given to the tool.

With the above and other objects in view which will appear as the description proceeds, the invention will now be described 25 with reference to the drawings wherein:

Figure 1 is a side elevation of a planer embodying the present invention.

Fig. 2 is a front elevation thereof.

Fig. 3 is a fragmentary plan view of the 40 machine illustrating the feed motor and its driving connections.

Fig. 4 is an enlarged fragmentary end view of the cross rail tool feeding mechanism.

Fig. 5 is a horizontal section thereof taken on the line 5—5 of Fig. 4.

Fig. 6 is a longitudinal section through the lost motion box feed mechanism and gear, taken on the line 6—6 of Fig. 7.

Fig. 7 is a transverse section thereof taken on the line 7—7 of Fig. 6.

Referring particularly to Figs. 1 and 2 of the drawings, 1 represents the planer bed, 2 the reciprocating table, 3 and 4 the uprights or housings and 5 the arch connect-

ing the uprights. Driving mechanism is provided for reciprocating the table 2 on its bed, and so far as certain features of the invention are concerned this driving mechanism can be of any usual or preferred 60 form. I prefer, however, to use an electric motor which is directly geared to the table and which is reversible to effect the reciprocation thereof, such a motor having especial advantages in connection with a 65 planer embodying the more characteristic features of my invention. A reversible electric motor is indicated in the drawings at 6, the gearing connections between it and the table being of any usual or preferred 70 form. When such a motor is used there is provided a suitable controller illustrated diagrammatically in the aforesaid patents and in my copending application, Serial No. 308,558, filed June 10th, 1920. For 75 operating certain parts of the controller and for other purposes there is provided a pilot switch 7. This switch is operated by means of a rod 8 connected to levers 9 and 10 which are engaged respectively by dogs 80 11 and 12 secured to the reciprocating table. These dogs are adjustable in position so as to regulate the length of the stroke.

Cooperating with the reciprocating table to act upon work carried thereby are one 85 or more cutting tools. In the construction illustrated there is a vertically movable cross rail 13 which is fitted to vertical guides on the uprights 3 and 4. Transversely movable along the cross rail 13 are one or 90 more (two being illustrated) tool heads 14 and 15. Transversely threaded shafts or screws 16 are provided to respectively control the transverse movements of the tool heads 14 and 15, and a splined shaft 16^a 95 is provided for operating the tools vertically in the usual manner. These screws or shafts 16 can be moved manually when desired by means of a crank 17 as illustrated. For moving one or more of the 100 tool heads by power, either to effect preliminary adjustment of the tools or to effect feeding thereof during the operation of the planer, I provide an independent electric motor which is shown in the drawings 105 at 18, it preferably being mounted upon the arch 5.

The mechanism so far specifically described is clearly shown and described in the aforesaid patents and since such mech- 110

the opposite direction. It will, therefore, be seen that in the relative position of the lugs as illustrated, the angular distance x plus the angular distance y represents the lost motion through which the member 29 passes in each direction of its oscillation. The gear 26 is therefore given an oscillatory angular movement equal to the oscillatory movement of the shaft 24 less the angular movement represented by the sum of the arcs x and y . The lugs 36 and 37 being on opposite sides of the gear 26, each lug is out of the path of adjustable movement of the other. By such a construction, the two lugs may be adjusted to a position directly opposite each other and provide therefor for a variable lost motion from 0° to 360° less the arcuate distance represented by the sum of the arcuate thicknesses of one of the lugs 38 and 38^a plus one of the lugs 36 and 37. It will therefore be seen that with the mechanism illustrated, the extent of tool feed may be very widely varied to suit the conditions of the particular work in hand and the engagement of either lug 36 or 37 with its respective lug 38 or 38^a provides an operative connection through the feed box for traversing the tools in either direction.

30 The side head 43, as illustrated in Fig. 1, is also adapted to be fed and traversed through the vertical feed shaft 21 and the lost motion feed connection illustrated at 25', 26', 27' and 28'. The details of this mechanism are the same as those described in connection with the cross rail tool feed mechanism and therefore need not be further described herein.

By engaging the clutch 44 with its driving gear 45, the cross rail 13 may be raised or lowered by means of the motor 18 operating through shaft 46 and vertical screws 47.

What I claim is:

45 1. In a planer, the combination of a reciprocating table, a tool head, a feed screw for moving the head, a feed motor, mechanism including a single driving connection from the motor to the feed screw for intermittently and automatically feeding the head from the motor in synchronism with the table reciprocation, and means for controlling the continuous operation of the motor for traversing the head, the feeding and traversing of the head taking place from the motor to the screw through the said single driving connection.

50 2. In a planer, the combination of a reciprocating table, a tool head, a feed screw for moving the head, a feed motor, mechanism including a single driving connection from the motor to the feed screw for intermittently feeding the head from the motor in synchronism with the table reciprocation, and means for controlling the continuous op-

eration of the motor for traversing the head, the feeding and traversing of the head taking place from the motor to the screw through the said single driving connection, and the said mechanism including means for varying the amount of feeding movement given to the head. 70

3. In a planer, the combination of a reciprocating table, a tool head, a feed screw for moving the head, a feed motor, mechanism including a single driving connection from the motor to the feed screw for intermittently and automatically feeding the head from the motor in synchronism with the table reciprocation, and means for controlling the continuous operation of the motor for traversing the head, the feeding and traversing of the head taking place from the motor to the screw through the said single driving connection, and the said mechanism including lost motion means for varying the amount of feeding movement given to the head. 75

4. In a planer, the combination of a reciprocating table, a tool head, a feed screw for moving the head, a feed motor, adjustable means between the motor and feed screw for varying the amount of feeding movement given to the head, mechanism including the said adjustable means for intermittently and automatically feeding the head from the motor in synchronism with the table reciprocation, and means for controlling the continuous operation of the motor for traversing the head, the feeding and traversing of the head taking place from the motor to the screw through the said adjustable means. 90

5. In a planer, the combination of a reciprocating table, a tool head, a feed screw for moving the head, a feed motor, adjustable means comprising a driving lug driven by the motor and a driven lug operatively connected to the feed screw for feeding the head, means for adjusting one of such lugs to vary the amount of feeding movement given to the head, mechanism including the said adjustable means for intermittently and automatically feeding the head from the motor in synchronism with the table reciprocation, and means for controlling the continuous operation of the motor for traversing the head, the feeding and traversing of the head taking place from the motor to the screw through the said adjustable means. 105

6. In a planer, the combination of a reciprocating table, a tool head, a feed screw for moving the head, a feed motor, a gear operatively connected to the screw and adapted to be driven by the motor, adjustable means comprising a pair of relatively adjustable lugs between the motor and gear for varying the amount of feeding movement given to the head, the said lugs being on opposite sides of the gear respectively, 110 115 120 125 130

means for relatively adjusting the said lugs, means adapted to be engaged by the lugs for driving the gear, mechanism including certain of the said means for intermittently and automatically feeding the head from the motor in synchronism with the table reciprocation, and means for controlling the continuous operation of the motor for traversing the head, the feeding and traversing of the head taking place from the motor to the screw through the said adjustable means.

7. In a planer, the combination of a reciprocating table, a tool head, a feed screw for moving the head, a feed motor, adjustable feeding means comprising a member driven by the motor and a member operatively connected to the feed screw, a lug on one of the members, a pair of relatively adjustable lugs comprising a part of the other member and adapted to engage the first lug, means for relatively adjusting said pair of lugs, mechanism including the said adjustable means for intermittently and automatically feeding the head from the motor in synchronism with the table reciprocation, and means for controlling the continuous operation of the motor for traversing the head, the feeding and traversing of the head taking place from the motor to the screw through the said adjustable means.

8. In a tool feeding mechanism, the combination of a feed screw, a feed shaft, a member operatively connected to the shaft, a second member mounted coaxially of the first member and operatively connected to the feed screw, a pair of relatively adjustable lugs mounted on one of the members in a relative position out of the path of movement of each other, and means on the other member adapted to be engaged by the said lugs for rotating the feed screw through a predetermined angular distance as the shaft is oscillated, the said predetermined angular distance depending upon the relative angular position of the said lugs.

9. In a tool feeding mechanism, the combination of a feed screw, a feed shaft, a member mounted coaxially of and operatively connected to the shaft, a second member mounted coaxially of the first member and operatively connected to the feed screw, a pair of relatively adjustable lugs mounted on one of the members in a relative position out of the path of movement of each other, means for relatively adjusting the lugs, and means on the other member adapted to be engaged by the said lugs for rotating the feed screw through a predetermined angular distance as the shaft is oscillated, the said predetermined angular distance depending upon the relative angular position of the said lugs.

10. In a tool feeding mechanism, the combination of a feed screw, a feed shaft, a

member mounted on and secured to the shaft, a second member mounted on the first member and operatively connected to the feed screw, a pair of relatively adjustable lugs mounted on one of the members in a relative position out of the path of movement of each other, and means on the other member adapted to be engaged by the said lugs for rotating the feed screw through a predetermined angular distance as the shaft is oscillated, the said predetermined angular distance depending upon the relative angular position of the said lugs.

11. In a tool feeding mechanism, the combination of a feed screw, a feed shaft, a driving member operatively connected to the shaft, a driven member mounted coaxially of the driving member and operatively connected to the feed screw, a pair of relatively adjustable lugs mounted on the driving member in a relative position out of the path of movement of each other, and means on the driven member adapted to be engaged by the said lugs for rotating the feed screw through a predetermined angular distance as the shaft is oscillated, the said predetermined angular distance depending upon the relative angular position of the said lugs.

12. In a tool feeding mechanism, the combination of a feed screw, a feed shaft, a member mounted on and secured to the shaft, a second member mounted on the first member and operatively connected to the feed screw, a pair of relatively adjustable lugs mounted on one of the members on opposite sides respectively of the second member in a relative position out of the path of movement of each other, and means on the other member adapted to be engaged by the said lugs for rotating the feed screw through a predetermined angular distance as the shaft is oscillated, the said predetermined angular distance depending upon the relative angular position of the said lugs.

13. In a tool feeding mechanism, the combination of a feed screw, a feed shaft, a member mounted on and secured to the shaft, a gear mounted on the member and operatively connected to the feed screw, a pair of relatively adjustable lugs mounted on the member at respectively opposite sides of the gear, means for relatively adjusting the lugs, and a pair of lugs on the opposite sides of the gear adapted respectively to be engaged by the adjustable lugs for rotating the feed screw through a predetermined distance as the shaft is oscillated, the said predetermined angular distance depending upon the relative angular position of the said lugs.

In testimony whereof, I hereto affix my signature.

HAROLD L. BLOOD.
